DESIGN FOR A BOTTLE RACK FOR VENDING MACHINES

Charles A. Melchert, Kansas City, Mo., assignor
to General Vender Mfg. Co., Kansas City, Mo.,
a corporation of Missouri

Application January 11, 1941, Serial No. 97,988

Term of patent 14 years

To all whom it may concern:

Be it known that I, Charles A. Melchert, a citizen of the United States, residing at Kansas City, in the county of Jackson and State of Missouri, have invented a new, original, and ornamental Design for a Bottle Rack for Vending Machines, of which the following is a specification, reference being had to the accompanying drawings, forming a part thereof.

Fig. 1 is a top plan view of the bottle rack for vending machines, showing my design.

Fig. 2 is an edge elevational view thereof; and

Fig. 3 is an inverted plan view thereof.

I claim:

The ornamental design for a bottle rack for vending machines, as shown.

CHARLES A. MELCHERT.
